UNITED STATES PATENT OFFICE.

FERDINAND E. DAVIS, OF ENGLEWOOD, AND OSCAR ABERLE, OF CHICAGO,
ILLINOIS, ASSIGNORS TO SIGMUND OPPENHEIMER, OF NEW YORK, N. Y.

MACHINE FOR CLEANING INTESTINES.

SPECIFICATION forming part of Letters Patent No. 363,370, dated May 24, 1887.

Application filed October 5, 1886. Serial No. 215,392. (No model.)

To all whom it may concern:

Be it known that we, FERDINAND E. DAVIS, residing at Englewood, Cook county, State of Illinois, and OSCAR ABERLE, residing at Chicago, in the county of Cook and State of Illinois, and citizens of the United States, have invented a new and useful Improvement in Machines for Cleaning Intestines, of which the following is a full description, reference being had to the accompanying drawings, in which—

Figure 1 is a plan. Fig. 2 is a side elevation. Fig. 3 is a detail showing the devices for driving the reel from the main shaft. Fig. 4 is an end view. Fig. 5 is an end view of the reel. Fig. 6 is a vertical section of the reel. Fig. 7 is a detail showing one of the eccentric levers used for holding the sliding frame in place. Fig. 8 is a plan of the main frame, somewhat reduced in size. Fig. 9 is a vertical section of one of the brushes. Fig. 10 is a detail, being a section at line $x x$ of Fig. 1. The housing is not shown in Figs. 2 and 4.

This machine is primarily designed to be used in cleaning beef-intestines to prepare them for various commercial uses. The machine may also be used for cleaning tripe and some other animal products.

The invention consists in the construction and combination of parts, as hereinafter more fully set forth and claimed.

In the drawings, A represents the main frame.

B is a portion of the main frame somewhat elevated, as shown, above the other parts.

C C' are two arms or supports extending out from B.

a, Fig. 8, are slots in the arms C C', and in the raised portion B of the frame A.

b are ways projecting upward from that part of the main frame marked B, and from the arms C C'.

D is a bar which rests upon the ways b, the bar being provided with grooves, into which the ways enter, and with downward projections, a'.

E is a shaft supported in bearings in the posts F, which extend upward from the bar D.

G is a brush on the shaft E.

c is a fixed pulley on the shaft E.

50 The bar D is held in place by bolts d, which

pass through two of the slots a, and by the eccentric levers e, which are pivoted in the lower ends of the bolts d.

f is a screw, provided with a hand-wheel, g, by means of which the sliding bar D can be 55 adjusted.

H, Figs. 2 and 10, is another sliding bar corresponding with D. It rests upon ways corresponding with b.

E' is another shaft supported in bearings in 60 posts F', which project upward from the bar H.

c' is a fixed pulley on the shaft E'.

G' is a second brush on the shaft E'.

The bar H may be held in place by bolts and eccentric-levers, as described for the bar D. 65

I I' are housings or guards over the two brushes, the lower ends of which housings are, as shown, secured one to each of the bars D H. (See Fig. 10.)

J, Figs. 1 and 10, is a small roller supported 70 in bearings secured to the housing I'.

The construction of the brushes is shown in Fig. 9, in which h is a head which is keyed to the shaft E. i is a collar upon the shaft E, the collar being screw-threaded. j is a head having a central opening, which is screw-threaded to correspond with the screw-thread upon the collar i. The heads h j are each provided with a notched groove, k, on the inside, which groove is cut into the heads at an angle. l is a suitable 80 cylinder, to which the brush material m is secured in any known manner. The cylinder l is of such size that its ends enter the grooves k in the heads h j, and by turning the head j the cylinder can be clamped in place between the two heads h j, and will be securely held. The

brush material may be rice-roots, Russian bristles, palmetto, or other known suitable substance. The brushes revolve in opposite directions, as indicated by arrows in Fig. 2, 90 and the screw-threads upon the collar i on one shaft are to be right-handed and on the other left-handed.

K is a driving-shaft supported in bearings on the main frame.

L L' are two pulleys, one of which is loose, and the other is a fixed driving-pulley driven by a belt which is not shown.

M is a shaft, one end of which carries a reel, N, which, as shown, is collapsible. n is a head 100

at one end of the reel. *o* are bars, each of which is pivoted at one end to the head *n*. *p* is a sliding hub on the shaft *M*.

q are rods. One end of each rod is pivoted 5 to the outer end of a bar, *o*, and the other end of each rod is pivoted to the hub *p*. (See Figs. 1, 5, and 6.) Each of the bars *o* is provided on one edge with devices for holding one end of the intestines. Three forms are shown, one 10 of which are notches *r*. Springs *r'* are another form. Small hooks *r''* are the third form.

s is a worm-screw on the shaft *K*, which engages with a worm-wheel, *t*, on one end of a shaft, *u*, supported in suitable bearings. The 15 other end of the shaft *u* carries a beveled gear-wheel, *v*, which engages with another beveled gear-wheel, *w*, on the reel-shaft *M*, and by these devices the reel-shaft is driven from the main shaft *K*.

20 *O* is a large sprocket-wheel on the shaft *K*.

P is a small sprocket-wheel on a shaft, *Q*, which is supported in bearings at the upper ends of standards *R*, which are secured to the frame.

25 *S* is a driving-pulley on the shaft *Q*.

T is a belt which drives the shaft *E*.

U is a belt which is crossed, and drives the shaft *E'*.

V is a chain on the sprocket-wheels *O P*.

30 The operation is as follows: One end of each intestine which is to be cleaned is to be passed in between the brushes, which can be readily done from their outer ends, there being an opening between the arms *C C'* and the brushes, 35 as shown in Figs. 8 and 10. The intestine is to be carried up over the roller *J* by the operator to the reel *N*, where one end may be passed to one of the holding devices on one of the bars *o*, and the machine being in motion the 40 movement of the reel will gradually draw the intestine between the two brushes, which, being in rapid motion, will thoroughly clean the intestines. When the reel is full the machine is to be stopped, the hub *p* can be

45 moved in or out a little on the shaft *M*, and the parts *o q*, being hinged, as aforesaid, the reel will partially collapse, and then the clean intestines on the reel can be easily removed. The parts of the reel can then be returned to 50 their former position ready for use again. The driving-pulley *L* may have about eighty revolutions per minute, which will give about two revolutions per minute to the reel and about sixteen hundred revolutions per minute to the

55 brushes. The shaft *Q* is driven by the chain *V*, which runs upon the sprocket-wheels *O P*.

The distance of the brushes from each other can be adjusted by moving the bar *D*, which can be done by loosening the eccentric levers *e*, and then turning the screw *f*. We have not 60 shown a screw for moving the bar *H*; but one may be provided, if desired.

It may be stated that cleaning beef-intestines consists chiefly in removing the mucous lining of the intestines. We do not limit our 65 machine and devices to the single use of cleaning beef-intestines.

What we claim as new, and desire to secure by Letters Patent, is—

1. In a machine for cleaning intestines, the 70 combination of a pair of rotary brushes, one of which is adjustable to and from the other, and brush-supports open at one end to facilitate the insertion of intestines between said brushes, substantially as described.

2. The combination of the arms *C C'*, having ways *b b*, the bars *D H*, and the rotary brushes *G G'*, said brushes being mounted on shafts supported in bearings on the bars *D H*, and one of said bars being adjustable to vary 80 the distance between the brushes, substantially as described.

3. The combination, with the rotary brushes *G G'* and brush-supports open at one end to facilitate the insertion of intestines between 85 said brushes, of a collapsible reel for receiving the cleaned intestines from the brushes, substantially as described.

4. The combination, with the rotary brushes *G G'*, of the shaft *M*, and a collapsible reel 90 mounted on said shaft and composed of the head *n*, the bars *o*, pivoted in said shaft and provided with devices for holding one end of the intestines, the sliding hub *p*, and rods *q*, pivotally connected with said bars and hub, 95 substantially as described.

5. The combination of the frame *A*, having raised portion *B* and arms *C C'*, the bars *D H*, one or both adjustable on said arms, the brush-shafts *E E'*, journaled in bearings on said bars, and carrying brushes *G G'* and pulleys *c c'*, the shaft *M*, carrying a collapsible reel, the driving-shaft *K*, having sprocket-wheel *O*, the shaft *Q*, having sprocket-wheel *P* and pulley *S*, the chain *V*, belts *T U*, and gearing for connecting the shafts *K M*, substantially as described.
